UNITED STATES PATENT OFFICE.

JOHN B. TEIXEIRA, OF NEAR SAN JOSE, CALIFORNIA, ASSIGNOR OF ONE-HALF TO
ANTONE M. BETTENCOURT, OF SAN JOSE, CALIFORNIA.

ROOFING TILE.

Application filed March 12, 1925. Serial No. 15,025.

To all whom it may concern:

Be it known that I, JOHN B. TEIXEIRA, a citizen of Portugal, and residing near San Jose, in the county of Santa Clara and State 5 of California, have invented certain new and useful Improvements in Roofing Tiles, of which the following is a specification.

It is the object of the present invention to provide a novel form of tile so formed 10 and constructed as to be readily mounted upon the framework of a roof and combined with additional tiles of identical form and construction to make a substantial, watertight, durable and fire-proof roof covering.

15 In the drawing:—

Figure 1 is a plan view of a portion of a roof embodying my invention.

Figure 2 is a section on line 2—2 of Figure 1.

20 Figure 3 is an enlarged plan view of a single tile.

Figure 4 is a section on line 4—4 of Figure 3.

25 Figure 5 is a section on line 5—5 of Figure 3.

Figure 6 is a section on line 6—6 of Figure 1.

Referring now more particularly to the drawing, I show at 1 the body portion of a 30 tile of suitable thickness and flat throughout the greater portion of its width and length, but curved downwardly at one end to form a lip 2 at substantially right angles to part 1. A slot 3 is formed in the edge of 35 said lip for the purpose hereinafter described. The end of the tile opposite to the curved end 2 is provided with an upstanding flange 4 offset a distance at one end as indicated at 5 to receive one end of flange 4 on the adjoining tile as shown in dotted lines 40 at 6 when the tiles are assembled on a roof frame.

Along one of the side edges of the tile body 1 is an upstanding flange 7 of the same 45 height as flange 4. This flange 7 carries a laterally extending overhanging part 8 provided with depending and spaced ribs 9 and 10 to form grooves 11 and 12 as shown. These parts 8—9—10—11—12 extend the 50 full length of plate 1 and follow its curvature from offset 5 to the end of lip 2.

Along the opposite side of body 1 is an upstanding flange 13 and parallel therewith and spaced a distance therefrom is an upstanding rib 14 forming a groove 15 there-

between, the parts 13—14 extending from end flange 4 to the end of lip 2.

The height of flange 13 and rib 14 is equal to the height of end flange 4 less the thickness of the overhanging part 8. 60

A shallow recess 16 is formed across the upper surface of part 8 where it abuts offset part 5, and two short feet 17 are formed on the under surface of body 1 beneath flanged end 4. A lug is also formed on the 65 under side of body 1 as at 18 and provided with a hole 19.

In assembling the tiles on a roof frame they are placed in rows with the parts 8—9—10—11—12 of one tile overlapping and 70 engaging the parts 13—14—15 of the adjoining tile, and each tile is secured to the roof frame 20 by means of a wire engaging the same and hole 19 in the tile.

The next higher row of tiles are now secured in staggered relation to the lower row, the slot 3 in the lip of each upper tile 75 engaging the recessed portion 16 in part 8 of the lower tile, and the lips 2 of the upper tiles lying against the front surfaces of the 80 flanges 4 of the lower tiles.

At the peak of the roof a ridge is provided as shown consisting of tile elements 21 provided with overlapping engaging 85 ends 22.

It may be seen from the foregoing that I have provided a construction which is 90 water-proof and fire-proof, substantial, strong, durable, economical to manufacture, and one in which the several parts are quickly assembled. In this construction a solid sheathing for the roof frame is not required as it is only necessary to provide suitable strips as 23 for carrying the feet 17, and any suitable means may be used for 95 securing the tiles to the roof frame.

It is to be understood, of course, that while I have herein shown and described but one specific embodiment of the invention, changes in form, construction and 100 method of application may be made within the scope of the appended claim.

I claim—

A roofing tile comprising a plate having 105 an upstanding flange extending its full width at one end and a downwardly curving lip at the other end, said lip having a notch formed therein and said flange having one end offset a distance to receive one end of the upstanding flange on an adjoin- 110

ing tile, and said plate having a pair of up-
standing spaced and parallel ribs of uni-
form height formed along one side edge to
form a groove the other side edge carrying
an upstanding flange and a laterally extend-
ing overhanging part carried by said flange,
said overhanging part having a pair of

spaced parallel ribs of uniform height de-
pending therefrom to form, in conjunction
with said last mentioned flange, a pair of 10
parallel grooves and a groove formed trans-
versely in its upper surface adjacent to said
first mentioned upstanding flange.

JOHN B. TEIXEIRA.
